(57) **CLAIM**

The ornamental design for a display for dishwasher, as shown and described.

DESCRIPTION

FIG. 1 is a front view of a display for dishwasher showing my new design; and,

FIG. 2 is a front view of a second embodiment of a display for dishwasher.

The broken line showing of the portion of the display is for the purpose of illustrating environmental structure and forms no part of the claimed design.

1 Claim, 2 Drawing Sheets**Fig. 1**

Fig. 2
